Patented Nov. 7, 1916.

FIG. 1.

FIG. 2.

FIG. 3.

Inventor:
Charles A. Simpson.

By his Atty. *Charles S. Godwin*.

UNITED STATES PATENT OFFICE.

CHARLES ASBURY SIMPSON, OF BOSTON, MASSACHUSETTS.

BOTTLE-STOPPER AND PIPETTE.

1,203,919.

Specification of Letters Patent.

Patented Nov. 7, 1916.

Application filed November 1, 1915. Serial No. 59,058.

To all whom it may concern:

Be it known that I, CHARLES ASBURY SIMPSON, a citizen of the United States, residing at Boston, in the county of Suffolk and State of Massachusetts, have invented new and useful Improvements in Bottle-Stoppers and Pipettes, of which the following is a specification.

My invention relates to pipette bottles and 10 is an improvement upon that class of pipette bottles in which the pipette has a member which, as a whole, serves as a stopper for a bottle and as a means for removing liquid from said bottle.

15 For ordinary liquids the pipette in use is adapted to fit the neck of a bottle by means of cork or rubber. For chemical reagents, caustic and corrosive liquids and various solvents, it is necessary that all parts of the pipette and stopper with which the liquid may 20 come in contact should be of glass or porcelain. To meet these requirements a glass pipette of sufficient length to reach the bottom of the bottle is sometimes enlarged in its central upper portion to form a conical plug or 25 stopper which is ground to fit the neck of a bottle as in the ordinary glass stopper and no cork or rubber is used excepting a small rubber bulb or equivalent at the extreme upper end of the pipette for the purpose of 30 applying suction. It is to this special class of pipette bottles that my invention belongs and to which the improvements of my invention over the prior art devices are directed.

35 In using pipette bottles as heretofore constructed the stopper for the bottle and the member whereby suction is applied to remove liquid from the bottle are made in one piece which it is always necessary to remove from the bottle and which serves not only as a stopper for the bottle in the sense of the ordinary bottle stopper, but also serves the function of removing liquid from the 40 bottle. The disadvantage of such a construction is that there is great liability to upset the bottle and spill the contents as well as danger of contamination of the liquid contents of the bottle by frequent removals 45 and insertions of the pipette. Also it is necessary in this class of pipette bottles to employ both hands, one to hold the bottle and one to remove the pipette from the bottle. To obviate these disadvantages I have invented a new and improved form of pipette

bottle which is especially adapted for use with chemical reagents, corrosive liquids and special solvents and which provides a better and quicker method for removal of small amounts of liquid than prior devices.

60 The objects of my invention are as follows: first, to permit the use of a pipette in removing small quantities of liquid from a stoppered bottle without removing the stopper and without inserting the pipette into the liquid contents of the bottle; second, to provide a shorter and more convenient form of pipette; third, to enable the use of a pipette by the employment of one hand only; fourth, to provide a convenient holder for 70 the pipette when the same is not in use; fifth, to provide a small bowl in the stopper as a receptacle for small amounts of liquid removed from the bottle by the pipette; sixth, to provide means for using a single 75 small pipette for bottles of various heights.

Having these objects in view, therefore, my invention consists in a pipette formed in two parts, one of said parts forming a stopper adapted to fit the neck of a bottle and 80 having a tubular portion extending therefrom to the bottom of the bottle, all as set forth in the following specification and particularly pointed out in the claims thereof.

85 Referring to the drawings: Figure 1 is a sectional elevation of a bottle with my improved stopper and pipette shown in connection therewith. Fig. 2 is a side elevation of the stopper and tubular extension. Fig. 3 is a side elevation of the pipette.

90 Like numerals refer to like parts throughout the several views of the drawings.

In the drawings, 5 is a bottle of any suitable form having a neck 6 to receive the stopper 7. Said stopper embodies an upper 95 part or head 8 which is circular in cross section and is of convenient size for grasping with the thumb and finger when inserting or removing the stopper from the bottle. The head 8 has a central portion hollowed out to 100 form a small bowl-shaped cavity or chamber 9. The chamber 9 forms a convenient receptacle for holding small portions of liquids when removed from the bottle by the pipette.

105 The intermediate portion 10 of the stopper is preferably conical in form on its periphery in order that it may fit the neck of a bottle so as to provide a liquid tight closure. The lower end of the stopper is per-

forated along its longitudinal axis by a hole 11, the hole 11 being extended into the main body portion of the stopper for a slight distance at 11' and the intermediate portion 12 of the bore of said stopper being conical in form and connecting the chamber 9 with the tubular extension 18.

The extension 18 may be formed by inserting a small tube in the body portion of 10 the stopper, the end of said tube being ground or tapered to fit accurately or tightly in said body portion. Said tubular extension 18 is of sufficient length to reach the bottom of the bottle when the stopper is inserted 15 in the neck of the bottle said extension should also have a small bore of $\frac{1}{16}$ " to $\frac{1}{8}$ " in diameter to give the best results. This tubular extension of the stopper may be formed in one piece where the stopper is 20 formed of glass. While I prefer to make said stoppers of glass, they may be made of porcelain, hard rubber, aluminum, or a combination of materials may be used in which a cork or rubber covering is utilized to cover 25 the exterior of the conical portion 10 of the stopper, but where the stopper is used for chemical or medicinal agents it is necessary that the same should be formed entirely of glass, porcelain or some rigid material which 30 is resistant to the action of said chemical or medicinal agent.

13 is a pipette formed in accordance with my invention and consists of a conical tip 14 which is formed to fit accurately within 35 the conical bore portion 12 of the stopper 7. The conical tip 14 is formed to fit accurately within the conical chamber 12 so as to form a continuous and practically air-tight connection with the extension tube 18, and its 40 length should preferably be only slightly more than the depth of the chamber 12. The mutual conformation and adaptation of the conical portion 14 of the pipette and of the chamber 12, together with the size of the extension tube 18, determines the successful 45 operation of this device. By varying the length of the extension tube 18 bottles of various depths may be used without changing the size or length of the pipette, and it 50 will be noted that said extension 18 forms a continuation of the pipette tube 14 when the pipette is inserted in the chamber 12. The conical portion 14 of the pipette extends 55 downwardly from a bulb 15 and a cylindrical stem 16 extends upwardly from said bulb to receive a collapsible bulb 17, preferably formed of rubber. The bulb 15 should be 60 of sufficient size to contain all of the liquid sucked up by the operation and prevent any 65 from entering the rubber bulb 17.

It will be seen that the pipette of my invention is much shorter and more convenient for use than the pipettes ordinarily used. It will thus be seen that the stopper hereinbefore specifically described has a bore ex-

tending therethrough, said bore comprising a conical intermediate portion, a tubular lower portion and an enlarged upper portion forming a chamber. It will be seen that by thus separating the pipette as a whole into two parts, namely, the stopper portion and the auxiliary stopper or pipette portion, the advantages hereinbefore set forth are secured and the pipette is much shorter and more convenient to use than pipettes heretofore required for similar purposes, namely, for the removal of small amounts of liquids from bottles.

In using the invention hereinbefore set forth, the stopper 7 with its tubular extension 18 is inserted in the neck 6 of the bottle 5 tightly enough to form a liquid and air-tight closure. When so inserted no liquid can escape when the bottle is tipped over, or even inverted, as the bore 11 of the tubular extension 18 of the stopper and the bore 11' in the main body portion of the stopper are so small in diameter that liquid is held in the bottle by pressure of the outside air. The rubber bulb 17 of the pipette is compressed by the thumb and finger of the user and while thus compressed the point of the pipette is inserted in the chamber 12 of the stopper using light pressure as far as it will go making practically an air-tight connection with the tubular extension 18. On releasing the pressure on the bulb a portion of the liquid contents of the bottle is sucked up into the pipette. If more liquid is desired the rubber bulb is again compressed without removing the pipette from the stopper, thus forcing air into the bottle and upon releasing the bulb the air pressure in the bottle forces the liquid up into the pipette.

This form of pipette bottle acts by suction 105 or compression or both combined. The liquid drawn up into the pipette may, if desired, be delivered into the bowl-shaped cavity 9 in the head of the stopper, where it will remain and not flow back into the bottle, being held by the air pressure within the bottle. This bowl-shaped cavity, therefore, furnishes a very convenient receptacle for moistening pellets of cotton, or inserting probes or other instruments. After use the liquid remaining in the bowl 9 can be sucked up by the pipette and thrown away or the pipette with liquid contents may be inserted in the stopper which serves as a pipette 110 holder and the liquid remains in the pipette securely sealed from the air until wanted. This form of pipette is especially convenient 115 for medicinal purposes.

While I have described the intermediate chamber 12 as being conical in shape, it is 125 evident that the form of this chamber may be varied and depart slightly from the conical shape, such, for instance, as to assume the shape of a conoid without departing from the spirit of my invention.

Having thus described my invention, what I claim and desire by Letters Patent to secure is:

1. In combination, a bottle, a stopper for 5 said bottle made of rigid material with a conical chamber formed on the longitudinal axis of said stopper, a tubular extension from the lower end of said chamber to the bottom of said bottle and a pipette having a 10 conical tip formed to fit said chamber.

2. In combination, a bottle, a stopper for 15 said bottle made of rigid material having a bore extending therethrough and comprising a conical chamber in its intermediate portion, a tubular lower portion and an enlarged bowl-shaped upper portion and a pipette, having a portion thereof formed to 20 fit into said conical chamber of said stopper and having an enlarged central portion forming a bulb.

3. In combination, a bottle and a tubular pipette extension having its upper part enlarged to form a conical stopper fitting the neck of said bottle, the bore of said tube 25 enlarged within its upper part to form two connected chambers, the uppermost chamber being bowl-shaped and the lower chamber being conical-shaped and a pipette having its lower part formed as a conical tip and its 30 middle portion enlarged to form a bulb, said conical tip being constructed to fit within said lower chamber in said tubular pipette extension, whereby a continuation or extension of the pipette to the bottom of the bottle 35 for the purpose of sucking up into the pi-

pette and removing from the bottle portions of the liquid contents is formed.

4. In combination, a bottle and a pipette in two parts, one part forming a permanent stopper constructed to fit the neck of said 40 bottle and having a conical bore with a tubular extension projecting from its lower end to the bottom of said bottle, the other part of said pipette constituting an auxiliary stopper and comprising a member having a 45 conical tip constructed to fit said conical bore and an enlarged central portion forming a chamber, the upper end of said member terminating in a tubular extension and a collapsible bulb attached to said tubular ex- 50 tension.

5. In combination, a stopper for a bottle having a conical bore and a tubular extension projecting from its lower end of substantial length and adapted to extend to the 55 bottom of said bottle, and a pipette having a conical tip constructed to fit said conical bore and an enlarged central portion forming a chamber, the upper end of said pipette terminating in a tubular extension and 60 a collapsible bulb attached to said tubular extension.

In testimony whereof I have hereunto set my hand in presence of two subscribing witnesses.

CHARLES ASBURY SIMPSON.
